[57] CLAIM

The ornamental design for an automotive trunk storage unit, as shown and described.

DESCRIPTION

FIG. 1 is a top perspective view of an automotive trunk storage unit showing my new design.

FIG. 2 is a front elevational view thereof.

FIG. 3 is a left end elevational view thereof, the right end elevational view being a mirror image of the left end shown.

FIG. 4 is a bottom plan view thereof.

FIG. 5 is a rear elevational view thereof; and,

FIG. 6 is a top perspective view thereof, with three of the flaps in open condition.
